UNITED STATES PATENT OFFICE.

JOHN WEBSTER HOWELL, OF JOHNSTOWN, PENNSYLVANIA.

THILL-COUPING.

SPECIFICATION forming part of Letters Patent No. 608,680, dated August 9, 1898.

Application filed October 29, 1897. Serial No. 656,833. (No model.)

To all whom it may concern:

Be it known that I, JOHN WEBSTER HOWELL, residing at Johnstown, in the county of Cambria and State of Pennsylvania, have invented a new and useful Thill-Coupling, of which the following is a specification.

This invention relates to improvements in thill-couplings; and the object of the same is to provide an improved coupling in which the thills may be quickly and readily positioned and locked therein and from which they may be instantly detached, the coupler being so constructed as to prevent rattling as the parts wear from use.

With the above object in view the invention consists of a coupler-head which is attached to the axle by clips and adapted to receive the thill-iron, a retaining-frame for engaging the iron and preventing the removal of the latter until the frame is raised, and a spring for retaining the frame in engagement with the thill-iron.

My invention further consists in the improved construction, arrangement, and combination of parts hereinafter fully described, and afterward specifically pointed out in the claims.

In order to enable others skilled in the art to which my invention most nearly appertains to make and use the same, I will now proceed to describe its construction and operation, having reference to the accompanying drawings, forming part of this specification, in which—

Figure 1 is a perspective view of my invention, a portion of the axle, to which it is attached, being shown. Fig. 2 is a top plan view of the same. Fig. 3 is a vertical longitudinal sectional view on the line 3 3 of Fig. 2. Fig. 4 is a detached perspective view of the retaining-frame. Fig. 5 is a side elevation showing the retaining-frame raised to permit the removal of the thill-iron.

Like letters of reference mark the same parts wherever they occur in the various figures of the drawings.

Referring to the accompanying drawings, A indicates the axle, to which the coupler-head is secured by means of the clip B, said coupler-head consisting of the forwardly-projecting arms C, enlarged at their extremities and formed with the rearwardly-extending

open-ended slots D to receive the trunnions E of the thill-iron F.

The arms C are cut out on their outer surfaces to receive the arms G of the retaining-frame H, said retaining-frame being pivoted to the coupler-head by means of the bolt I, which passes therethrough and is secured by the nut J. The arms G of the retaining-frame are also enlarged at their outer ends and provided with the open-ended slots K, which are formed on a different angle from the slots D, so that when said retaining-frame is moved downward the trunnions of the thill-iron will be received by said slots and the removal of the iron prevented until the retaining-frame is again raised.

For holding the retaining-frame normally pressed downward I provide the spring M, which is angular in shape and is coiled about the bolt I, with its angular portion engaging the clip and its extremities resting upon the connecting-bar of the retaining-frame.

When it is desired to attach the thill-iron to the coupler-head or remove the same therefrom, the retaining-frame is raised by means of its connecting-bar, when said iron may be inserted in the slotted arms of the head or removed therefrom.

Accidental displacement of the thill-iron is absolutely impossible when the retaining-frame is lowered, as will be readily understood, and the spring pressing said frame against the trunnions of the thill-iron prevents rattling of the parts.

From the above description it will be seen that I have produced an improved thill-coupling by means of which the thills may be quickly and readily attached to the vehicle or removed therefrom, and also in which the number of parts are reduced to a minimum, thus rendering the coupler simple and cheap to manufacture.

While I have illustrated and described the best means now known to me for carrying out my invention, I do not wish to be understood as restricting myself to the exact details of construction shown and described, but hold that any slight changes or variations, such as might suggest themselves to the ordinary mechanician, will properly fall within the limit and scope of my invention.

Having thus fully described my invention,

what I claim as new, and desire to secure by Letters Patent of the United States, is—

1. A thill-coupler comprising an axle-clip having forwardly-extending arms thereon, 5 with rearwardly-extending slots adapted to receive the trunnions of the thill-iron, a retaining-frame pivoted to the said arms having forwardly-extending arms provided with open-ended slots adapted to engage the trunnions of the thill-iron, a connecting-bar for said retaining-frame adapted to limit the movement of the same and by means of which it is raised, and a coiled spring surrounding the pivotal shaft of the retaining-frame, one 10 end of which is adapted to bear against the axle-clip and the other end against the retaining-frame, substantially as described and for the purpose stated.
2. A thill-coupler comprising an axle-clip 15 having forwardly-extending arms provided with rearwardly-extending slots adapted to

receive the trunnions of the thill-iron, shoulered recesses provided in the outer sides of said forwardly-extending arms, a retaining-frame adapted to fit in said recesses having 20 slots formed therein disposed at a different angle from those of the clip-arms, a bolt for pivotally connecting said frame to the clip-arms, a connecting-bar for said retaining-frame for limiting its movement and by means 25 of which it is raised, a spring coiled around the said pivotal bolt, one end of which is adapted to bear against the axle-clip and the other end upon the connecting-bar for holding said retaining-frame normally downward 30 and closing the open-ended slots of the clip-arms, substantially as described.

JOHN WEBSTER HOWELL.
